(CL. D58—13)

To all whom it may concern:

Be it known that I, Ernest R. Erickson, a citizen of the United States and a resident of Des Moines, in the county of Polk and State of Iowa, have invented a certain new, original, and ornamental Design for a Divider for a Milk Bottle Case or the like, of which the following is a specification, reference being had to the accompanying drawing, forming a part thereof.

Figure 1 is a perspective view of a divider for a milk bottle case, showing my new design.

Figure 2 is an enlarged plan view thereof.

Figure 3 is an enlarged sectional view on the line 3—3 of Figure 1, and

Figure 4 is an enlarged sectional view on the line 4—4 of Figure 1.

I claim:

The ornamental design for a divider for a milk bottle case or the like, substantially as shown.

ERNEST R. ERICKSON.
